FIG. 2

UNITED STATES PATENT OFFICE.

RONALD A. McCANN, OF NEW BRUNSWICK, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,271,592.

Specification of Letters Patent.

Patented July 9, 1918.

Application filed August 19, 1914. Serial No. 857,432.

To all whom it may concern:

Be it known that I, RONALD A. McCANN, a citizen of the United States, residing at New Brunswick, in the county of Middlesex and State of New Jersey, have invented certain new and useful Improvements in Railway Signaling, of which the following is a specification.

My invention relates to railway signaling, and particularly to signaling for stretches of single track over which traffic moves in both directions, such for example, as stretches of single track between passing sidings.

I will describe two forms of signaling systems embodying my invention, and will point out the novel features thereof in claims.

In the accompanying drawings, Figure 1 is a diagrammatic view showing a stretch of track having applied thereto one form of signaling system embodying my invention, the signals being of the two-position type indicating clear and danger. Fig. 2 is a view showing a modification of the circuits shown in Fig. 1.

Similar reference characters refer to similar parts in each of the views.

Referring first to Fig. 1, A—B is a stretch of single track between two passing sidings E and F, over which stretch traffic moves in both directions. Traffic through this stretch from east to west is governed by signals S¹, and S³ and traffic from west to east is governed by signals S² and S⁴. As here shown, signals S¹ and S² are located at the entrance ends of the stretch, while signals S³ and S⁴ are located at intermediate points in the stretch and are staggered in relation to each other.

Insulated joints 1 divide the stretch A—B into several successive sections A—C, C—D and D—B, and as here shown the intermediate signals S⁴ and S³ are located at points C and D respectively. Each section is further divided by insulated joints 1 into two sub-sections, as A—H and H—C for section A—C, and each sub-section is provided with a track circuit. Each track circuit comprises the rails of the sub-section, a battery b, and a track relay, the latter being designated by the reference character T, with the same exponent as that of the adjacent signal which governs traffic through the corresponding sub-section.

A signal relay is provided for the control of each signal and designated by the reference character R with an exponent corresponding to the exponent of the signal which the relay controls. Each signal is provided with a circuit which is controlled by the corresponding signal relay. For example, the circuit for signal S³ is from battery P³, through wire 73, contact 3 of relay R³, wire 4, mechanism of signal S³, wire 5, contact 6, wires 7 and 8 to battery P³. The circuit for each of the other signals is similar to that just traced for signal S³.

Signal relay R' for signal S' is controlled by contact 35 of signal relay R³ and signal relay R³ is provided with a circuit which is controlled by each of the track relays for the sections in advance of the signal S³ and also by a back contact of an auxiliary relay X⁴. The circuit for signal relay R³ is from battery P², through wire 112, contact 113 of track relay T², wire 114, contact 115 of track relay T³, wire 116, back contact 117 of relay X⁴, wire 118, contact 119 of track relay T⁴, wire 120, contact 121 of track relay T³, wire 122, relay R², wire 123, and common wire O to battery P². Signal relay R² for signal S² is similarly controlled by a contact of relay R⁴ and the latter relay is similarly controlled by each of the track relays for the sections in advance of signal S⁴.

The circuit for signal relay R' is provided with a branch around contact 35 of relay R³, which branch is controlled by an auxiliary relay X³; similarly, the circuit for relay R² is provided with a branch around contact 97 of relay R⁴, which branch is controlled by auxiliary relay X⁴. Each auxiliary relay is controlled by a pick-up circuit and a holding circuit. The pick-up circuit for auxiliary relay X³ is from battery P², through wires 73, 58 and 88, contact 46 of track relay T², wire 87, contact 47^a, wire 86, relay X³, wire 80, to battery P². The holding circuit for this relay is from battery P², through wires 73 and 58, contact 79 of track relay T³, wire 78, contact 39 of relay X³, wire 64, relay X³, and wire 80 to battery P². This holding circuit is provided with a branch around contact 79 of track relay T³, which branch is from wire 58 through wire 50, contact 47, wire 81, to wire 78. By virtue of this branch, it will be seen that the holding circuit of relay X³ remains closed as long as signal S³ remains in the danger position.

Auxiliary relay X^4 is provided with a pick-up circuit and a holding circuit which circuits are similar to those just traced for relay X^3 .

- 5 The operation of the system shown in Fig. 1 is as follows: As a westbound car or train enters sub-section B—N, track relay T' will open, which opens the circuit for signal relay R' at contact 45, so that signal S' changes to danger. The opening of track relay T' also opens the circuit for signal relay R^4 at contact 44, thus causing signal S^4 to go to the danger position. The opening of signal relay R^4 opens the circuit for signal relay R^2 , thus putting signal S^2 to the danger position.

As the train moves into sub-section N—D, track relay T^6 will be opened, and track relay T' will close, but the position of the signals will not change since the signal relay circuits controlled by these two relays are the same. The opening of track relay T^6 closes at contact 46 the pick-up circuit for auxiliary relay X^3 .

- 25 As the train enters sub-section D—Q, track relay T^3 opens, thus causing relay R^3 to open, thereby allowing signal S^3 to change to danger. The opening of track relay T^3 closes the holding circuit for relay X^3 so the latter 30 remains closed even after track relay T^6 closes. As soon as track relay T^6 is picked up, relay R' becomes energized by a circuit from one side of battery P^3 through wires 73 and 83, contact 84 of auxiliary relay X^3 , wire 68, contact 18 of track relay T^6 , wire 70, contact 45 of track relay T' , relay R' , wire 72, and common return wire O to the other side of battery P^3 . Upon the closing of signal relay R' signal S' will 35 change to the clear position thus allowing a following westbound train to enter sub-section B—N. As the first train passes through the remainder of the stretch it holds open the circuit for relay R^3 by one or another of track relays T^4 , T^5 or T^2 , hence signal S^3 continues to indicate danger. Auxiliary relay X^3 continues to be closed as long as signal S^3 indicates danger, because of contact 47 operated by this signal, hence 40 signal S' continues at clear unless a following train enters the stretch. As the train enters section C—H it closes at the contact of relay T^5 the pick-up circuit for relay X^4 , but this circuit is then open at contact 47^a of signal S^4 , and this signal is at danger because the circuit for relay R^4 is open at the back contact of relay X^3 ; hence relay X^4 does not close.

The operation of the apparatus shown in Fig. 1 during the movement of a train through the stretch from west to east would be similar to the operation just explained.

Referring now to Fig. 2, the arrangement of signals here shown is the same as in Fig. 1, but the control of the signal relays is

somewhat different. In Fig. 2 the signal relays R' and R^3 for the westbound signals are connected in multiple and are energized from battery P^2 , whereas the relays R^2 and R^4 for the eastbound signals are also connected in multiple and are energized from battery P^4 . For example, the circuit for relay R^3 is from battery P^2 through wire 89, contact 92 of track relay T^2 , wire 93, contact 94 of track relay T^5 , wire 95, back contact 75 97^a of auxiliary relay X^4 , wire 98, contact 99 of track relay T^4 , wire 100, contact 101 of track relay T^3 , wire 102, relay R^3 , wire 124, and common wire O to battery P^2 . The circuit for relay R' leaves this circuit at wire 80 102 and passes through wire 103, back point of contact 84 of auxiliary relay X^3 , wire 104, contact 18 of track relay T^6 , wire 70, contact 45 of track relay T' , wire 71, relay R' , and wire 74 to common wire O. 85

Auxiliary relay X^3 is arranged when energized to disconnect relay R' from the multiple circuit just traced and to connect it with battery P^3 , and similarly relay X^4 is arranged when energized to disconnect relay 90 R^2 from its multiple circuit and to connect this relay with battery P^4 . These auxiliary relays X^3 and X^4 are provided with pick-up and holding circuits which are similar to those previously traced herein for the auxiliary relays in Fig. 1.

The operation of the apparatus shown in Fig. 2 is as follows:

As a westbound car or train enters sub-section B—N, it opens track relay T' , thereby 100 opening relay R' and causing signal S' to change to danger. The opening of track relay T' also opens the multiple circuit including signal relays R^2 and R^4 , so that signals S^2 and S^4 change to danger. As the 105 train proceeds into sub-section N—D, it causes no change in the signal indications, but it closes the pick-up circuit for auxiliary relay X^3 , which relay then closes. Then as the train proceeds into sub-section D—Q, the 110 opening of track relay T^3 opens signal relay R^3 , so that signal S^3 changes to danger. Relays X^3 and T^6 , being now closed, relay R' is energized from battery P^3 so that signal S' 115 changes to clear, thereby permitting a following westbound train to enter the stretch. As the train proceeds through the remainder of the stretch it holds signal relay R^3 opened by one or another of track relays T^4 , T^5 or T^2 , so that signal S^3 continues to indicate 120 danger, and auxiliary relay X^3 continues to be closed by virtue of contact 47, so that signal S' continues in the clear position unless a following westbound train enters the stretch. 125

The operation of the apparatus shown in Fig. 2 during the passage of an eastbound car or train through the stretch is the same as the operation of the passage of a westbound car or train.

Although I have herein shown and described only certain forms of railway signaling systems embodying my invention, it is understood that various changes and 5 modifications may be made therein within the scope of the appended claims without departing from the spirit and scope of my invention.

Having thus described my invention, what

10 I claim is:

1. In combination, a stretch of railway track, track circuits for the stretch including track relays, two end signals for governing traffic into said stretch from opposite directions, two intermediate signals located respectively in advance of said end signals, a signal relay for each signal, a circuit for the signal relay for each end signal which circuit is controlled by the signal relay for 15 the adjacent intermediate signal and by the track relays for the stretch between said two signals, a circuit for each intermediate signal relay controlled by the track relays for that portion of the stretch in advance 20 of the intermediate signal, an auxiliary relay for each intermediate signal relay for rendering said relay ineffective to control the end signal relay in the rear; a pick-up circuit for each auxiliary relay including a 25 contact operated by the adjacent intermediate signal and closed when the signal indicates clear, and a back contact of a track relay in the rear of said signal; and a holding circuit for each auxiliary relay including a 30 back contact of a track relay in advance of said intermediate signal, and a front contact of the auxiliary relay.
2. In combination, two successive sections of a railway track, two signals located respectively adjacent the entrance ends of said 40 sections, track circuits for each section including track relays, a signal relay for each signal, means for controlling the signal relay for the rear signal by the track relays for 45 both sections and for controlling the signal relay for the signal in advance by the track relays for the section in advance, an auxiliary relay for removing the signal relay for the section in the rear from control by 50 the track relays of the section in advance, a pick-up circuit for said auxiliary relay controlled by the signal relay for the section in advance and by a back contact of the track relay for the forward track circuit 55 of the section in the rear, and a holding circuit for said auxiliary relay controlled by the auxiliary relay itself and by the signal relay for the section in advance.
3. In combination, two successive sections 60 of a railway track, two signals located respectively adjacent the entrance ends of said

sections, track circuits for the sections including track relays, a signal relay for each signal, means for controlling the signal relay for the rear signal by the track relays 65 for both sections and for controlling the signal relay for the signal in advance by the track relays for the section in advance, an auxiliary relay for rendering the track relays of the section in advance ineffective 70 to control the signal relay for the section in the rear, a pick-up circuit for said auxiliary relay controlled by the signal relay for the section in advance and including a back contact of a track relay for the section in the 75 rear, and a holding circuit for said auxiliary relay controlled by the signal relay for the section in advance.

4. In a signaling system for railways, in combination: a trackway divided into track 80 circuited blocks each having a track relay; a signal for governing the traffic in one direction over said trackway; a circuit for controlling said signal; means controlled by the track relay of the block following the 85 block protected by said signal for controlling said signal controlling circuit; an auxiliary circuit for nullifying the controlling effect produced by said means on said signal controlling circuit; a relay for controlling 90 said auxiliary circuit; and a circuit controlled jointly by the track relays of the block protected by said signal and of the following block for energizing said relay, said last-mentioned circuit being established 95 when the first block is occupied by a train and the second block is unoccupied.

5. In a signaling system for railways, in combination: a stretch of trackway divided into track circuited blocks each having a 100 track relay; a signal for governing traffic in one direction through said blocks; a circuit for controlling said signal; means controlled by the track relay of the block following the block protected by said signal for controlling 105 said signal controlling circuit; means for nullifying the controlling effect produced by the said means on said signal controlling circuit; the initial operation of said last-mentioned means being controlled 110 jointly by the track relays of the block protected by said signal and the following block; and means for holding said last-mentioned means in its operated condition while the track relay of said following block is de- 115 energized.

In testimony whereof I affix my signature in presence of two witnesses.

RONALD A. McCANN.
